ACETYLENE GENERATOR

Maurice P. De Motte, Indianapolis, Ind., assignor to Oxfeld Acetylene Company, a corporation of West Virginia

Application July 17, 1937, Serial No. 154,159

14 Claims. (Cl. 48—53.3)

This invention relates to acetylene generators and more particularly to the carbide feeding mechanism of acetylene generators of the carbide-to-water type.

5 The novel features of this invention are particularly adaptable for use with the improved carbide feeding and gas pressure control mechanism for acetylene generators of the carbide-to-water type disclosed in Patent No. 2,106,972 granted to M. P. De Motte on February 1, 1938, of which this is a continuation-in-part.

10 The supply of carbide to the gas generating chamber of these generators is usually automatically controlled by the pressure of the generated gas. A pressure responsive diaphragm is provided which, on one side, is exposed to the pressure within the generating chamber. The opposite side of this diaphragm is engaged by a spring, the expansive force of which may be adjusted to a predetermined operating pressure. Often, this force is so great that a considerable amount of effort is required to close the carbide feed valve when it is desired to interrupt the generation of acetylene and the valve operating mechanism 15 may be unduly strained. To overcome this difficulty, in the generator described in the above patent, a lost motion connection is desirably provided between the carbide feed valve and the pressure responsive diaphragm.

20 However, when an acetylene generator stands idle for any length of time, moisture in the atmosphere within the generator body may cause a slight slaking of carbide at the mouth of the hopper outlet. The moist carbide residue resulting from this slaking action tends to cause a sticky condition between the carbide valve and the valve seat. In generators of the type disclosed in the above-identified patent, and wherein the force of gravity acting on the lever and valve is relied upon to overcome the lost motion 25 between the carbide feed valve and the diaphragm when the generation of acetylene is resumed, the sticky condition mentioned above may at times be serious enough so that opening of the carbide feed valve is impossible. It is therefore desirable to provide means incorporated in the carbide feed valve mechanism to insure positive opening of the valve.

30 Furthermore, in manually initiating or resuming the generation of acetylene, the automatic control mechanism may not immediately function as a result of the lack of pressure in the generating chamber. An inexperienced operator may under such conditions open the carbide feed valve to its full extent or hold it open too long a

time, thereby permitting an excess of carbide to enter the generating chamber and consequently cause a rapid rise in pressure before the control mechanism becomes effective. Means must therefore be provided to automatically prevent an excess of carbide being fed to the generating chamber when the generation of acetylene is manually initiated.

35 It is therefore among the objects of this invention to provide an automatically operated carbide feeding mechanism which is simple in construction, easily manipulated, positive in operation and prevents excessive carbide feeding when acetylene generation is initiated.

40 These and other objects of the invention will in part be obvious and in part become apparent from the following description when read in conjunction with the accompanying drawing, in which:

45 Fig. 1 is a view of a generator with which the improved carbide feeding mechanism is to be used;

50 Fig. 2 is a sectional view taken on the line 2—2 of Fig. 1; and

55 Fig. 3 is a sectional view taken on the line 3—3 of Fig. 2, and illustrating the improved carbide feeding mechanism of the invention.

60 The invention, as illustrated in the drawing, may be embodied in an acetylene generator of the carbide-to-water type, described in the above-identified patent and which may include a closed casing of symmetrical contour having a water-containing and gas-generating lower portion A and a somewhat smaller carbide-containing and gas-storage upper portion B. The upper end of the lower portion A may taper inwardly and upwardly so as to merge with the upper portion B which may be provided with a conical top C. In order to provide access to the interior of the generator, the meeting portions of sections A and B may be respectively provided with separable flanges 10 and 12 suitably joined by conventional means such as a plurality of bolts 14, and appropriate hinges 15.

65 The upper section B may also be provided with a suitable compartment or chamber D within which the accessory equipment, with which such generators are usually provided, may be enclosed and protected by a suitable closure such as doors 16 and 18.

70 The compartment D is preferably within the general outline of section B, with which the doors 16 and 18 substantially conform. The generator may be further provided with conventional features such as a carbide charging door 20, gas-

outlet manifold 22, water-filling plug 24, overflow plug 26, sludge agitator 28, residue or drain valve 30, anchoring eyelet 32, handle 34, and charging platform 36.

- 5 A carbide hopper E having a downwardly tapering wall or bottom 38 may be mounted within the upper portion of section B. The margin of the hopper may be rigidly secured to the inner wall of section B by an impervious joint, such as an autogenous weld. The lower end of the carbide hopper E may be provided with a suitable depending spout 40 having a carbide outlet opening 42 therein. For convenience in attaching adjacent accessories and to facilitate removal of the outlet, the spout 40 may be secured to an annular hopper casting or ring 44 by suitable means such as a plurality of bolts 46, and the ring 44 may in turn be rigidly secured along a suitable opening in the bottom of the hopper by conventional means, such as a weld 48. The lower portion of the spout 40 may be provided with a drip flange 50 and this flange may be provided with an internal annular groove 52 adjacent and below the outlet 42, in which an annular compressible valve seat 54 of soft rubber or the like is removably secured by a supporting retainer plate 56 and an interfitting spring ring 58. The opening in the annular valve seat 54 may be of substantially the same size and substantially in alignment with the outlet opening 42 with which it cooperates and forms a part, and the flow of carbide from within the hopper to the outlet opening may be controlled by a carbide valve 60 that seats on valve seat 54 and forms a fluid-tight seal through which no water or moisture can enter the hopper and cause generation of gas when the valve is closed.

10 The carbide valve may form a part of a carbide-feed and gas-pressure control mechanism 40 F which may be detached from the generator as a unit. As the control unit F is fully described in the above-entitled patent, no further description is believed necessary here except to state that it includes a flexible diaphragm 62 upon which the gas pressure within the generator is balanced by one or more expanding springs, such as 64 and 66, which springs may be compressed within a suitable housing 68 in operative relation with the diaphragm which 15 in turn is operatively connected with the carbide valve 60. The desired operating pressure imposed on the springs 64 and 66 is adjusted by means of an adjusting screw 70 which operates on the springs 64 and 66 through a movable spring pressure plate 72. At the opposite end, the springs 64 and 66 engage a second spring pressure plate 74 which cooperates with the flexible diaphragm 62.

20 One of the features of the present invention resides in an improved connecting means between the diaphragm 62 and the carbide feed lever 80, to the inner end of which is pivotally secured, as by a pin 82, the carbide valve 60. An inner plate 84, in engagement with the pressure plate 74, and an outer plate 86 are secured, by means of a bolt 88 and a nut 90, to the diaphragm 62. The bolt 88 is formed with a forked end 92 in which is pivotally secured, as by means of a pin 94, the inner end of a link 96. In the outer 25 end of the link 96 is cut a slot 98 receiving a pin 100 attached to the carbide feed lever 80. The slot 98 and pin 100 form a lost motion connection between the diaphragm and the carbide feed lever.

30 The lever 80 may be pivotally mounted on a

suitable pivot pin 102 extending across an appropriate slot formed by lugs 104 of a feed lever support 106 that may be integral with a flange ring 108. This flange ring is secured by suitable means, such as a plurality of bolts 110, to an outwardly offset flange 112 formed on the inner end of housing 68. The diaphragm 62 is clamped between ring 108 and flange 112.

35 A spring seat 114 is formed on the carbide feed lever 80, and a resilient member such as a spring 116 surrounds the lost-motion connection and extends between this spring seat and the plate 86, tending to urge the pin 100 to the right in slot 98. An equivalent form of valve-operating mechanism including a lost-motion connection surrounded by a spring, is described and shown but not claimed in the copending application of Maurice P. De Motte et al., Serial No. 138,752, filed April 24, 1937.

40 For the purpose of holding the carbide valve closed when desired, such as when the generator is moved or when it is recharged, suitable means may be provided for operating the valve manually. This manual operating means may include a valve-closing arm or locking lever 118 integral with the lever 80, and in operative relation with a rotatable member such as a cam 120 formed with suitable cam surfaces 122, 124, and 126, and a lug 128 which forms part of an interlocking means preventing the maximum opening of the valve 60 until a predetermined pressure has been established in the generator. Cam 120 is fixedly mounted on an operating shaft 130, one end of which is provided with a suitable manually movable member, such as a handle 132 which is preferably located outside the generator casing within the accessory compartment D. The shaft 130 is mounted in a bearing 134 which may be integral with the spout 40.

45 In the position of the feeding mechanism shown in Fig. 3, the cam 120 has been rotated clockwise to bring the cam surface 122 into engagement with the arm 118, thereby forcing this arm upwardly and locking the feed valve 60 in closed position. The residual pressure in the generating chamber will cause the diaphragm 62 to remain in a position somewhat to the left of the position it assumes when the valve 60 is open to admit carbide. The springs 64 and 66 will be under compression and the pin 100 will be at or near the right hand end of the slot 98. If the generator remains idle for a considerable period of time, or if the residual gas is drawn off, the drop in gas pressure will permit the springs 64 and 66 to force the diaphragm 62 to the right. The feed lever 80 remains stationary, so the pin 100 will move to the left relative to the slot 98 in the link 96.

50 If it is desired to resume the feeding of carbide to the generating chamber, the cam 120 is rotated counterclockwise. The initial movement of the cam is limited by engagement of the lug or stop 128 with the end of arm 118 so that the cam surface 124 is disposed beneath this arm, thereby limiting the opening movement of the valve 60. The small amount of carbide permitted to enter the generating chamber by the initial opening movement of the valve 60 reacts with the water therein to generate acetylene gas at a rate just sufficient to cause the pressure to slowly increase. As the pressure rises within the generating chamber, the diaphragm 62 is moved to the left and closes the valve 60. The arm 118 will then have been moved upwardly to its full extent and in this position the cam 120

5 may be further rotated in a counter-clockwise direction to move the lug 128 beneath the arm 118 and past the same, and bring the cam surface 126 to a position below the arm 118. When this last cam surface is disposed below the arm 118, the valve may open to its full extent and is then fully under control of the automatic feed control unit.

10 When it is desired to stop the generation of acetylene gas, the operator will rotate the cam 120 clockwise until the cam surface 122 strikes the arm 118 forcing this arm upwardly and closing the feed valve 60. In this operation, the force of the springs 64 and 66 will not have to 15 be overcome as the pin 100 may move to the left in the slot 98 compressing the spring 116.

20 The spring 116 is of sufficient rigidity to take up all play in the lost motion connection and to insure that a positive opening movement of the valve will take place when the locking mechanism is released. This will force the valve away from the valve seat even though a slight slaking of the carbide may tend to cause a sticky 25 condition between the valve and the valve seat. Thus, when this spring is used, gravity is not relied upon to open the valve 60.

25 The lug 128 is of sufficient height to prevent the cam 120 being turned to allow the valve 60 to become fully open until the gas pressure in the generating chamber is sufficient to cause the automatic control mechanism to function. When the gas pressure has reached this predetermined 30 value, the cam 120 may be turned further in a counter-clockwise direction, as explained above, and the valve will then be fully under the control of the automatic mechanism.

35 The above-described mechanism retains the advantages of the lost motion connection, which permits the valve to be closed without overcoming the full force of the springs 64 and 66, while insuring a positive opening of the valve under all conditions. By the use of the spring 116 disposed between the diaphragm 62 and the lever 80, desirable features of the lost motion mechanism may thus be retained without the disadvantage due to the lack of a positive connection 40 between the feed lever and the diaphragm.

45 Although the various features of the improved generator have been shown and described in detail to fully disclose one embodiment of this invention, it will be evident that numerous changes may be made in such details and certain features may be used without others, without departing from the principles of the invention.

50 What is claimed is:

55 1. An acetylene generator including in combination, a hopper having an outlet; a valve controlling such outlet; means responsive to a predetermined gas pressure within such generator for controlling the operation of said valve; and means for preventing the maximum opening of said valve at least until said predetermined pressure has been established within said generator, said means comprising a pivotally mounted lever connected to said valve and to said pressure-responsive means and a rotatable cam for engaging said lever, said lever and said cam being provided with interlocking means for preventing rotation of said cam to a position permitting 60 the maximum opening of said valve before said predetermined pressure is established.

65 2. An acetylene generator including in combination, a hopper adapted to contain calcium carbide and having an outlet; a valve controlling said outlet; a pressure-responsive diaphragm

70 mounted in said generator; a lever pivotally mounted on said generator; said lever being pivotally connected to said valve and connected to said diaphragm through a lost motion connection; and a spring bearing against said lever and said diaphragm and surrounding said lost motion connection. 75

7. An acetylene generator as claimed in claim 2, including means engaging said lever for locking said valve in its closed position, said means being rotatable to a position in which said valve may open a limited amount and including a stop for engaging said lever to prevent further rotation of said means until said valve has been closed through the action of said pressure-responsive diaphragm. 10

8. An acetylene generator as claimed in claim 2, including a rotatable member for engaging said lever and locking said valve in closed position, said member being rotatable to a position in which said valve may open a limited amount and including a stop for engaging said lever to prevent further rotation of said member until said valve has been closed by said pressure-responsive means; said stop being of a height sufficient to permit it to pass said lever when said valve is closed, whereby said member may then be rotated to a position in which said valve may open to its full extent. 15

9. An acetylene generator as claimed in claim 2, in which said lost motion connection includes a link, said link being connected to said diaphragm by a fixed pivot and to said lever by a slot and pin connection. 20

10. An acetylene generator as claimed in claim 2, including means for locking said valve in closed position; said spring acting to force said lever away from said pressure-responsive diaphragm to positively open said valve when said locking means is released. 25

11. An acetylene generator as claimed in claim 2, in which said lost motion connection includes a link connected to said diaphragm by a fixed pivot and to said lever by a slot and pin connection; means for locking said valve in its closed position; said lost motion connection permitting said spring to be compressed between said diaphragm and lever when said valve is locked in its closed position; and said spring expanding to force said lever away from said diaphragm to insure positive opening of said valve when said locking means is released. 30

12. An acetylene generator including in combination, a hopper adapted to contain calcium carbide and having an outlet; a valve controlling said outlet; a valve lever pivotally mounted within said generator and pivotally connected to said valve; a pressure-responsive diaphragm mounted in said generator; said valve lever being connected to said pressure-responsive diaphragm through a linkage including a slot and pin connection; a spring bearing against said diaphragm and said valve lever and surrounding said linkage; an arm rigidly secured to said valve lever; a manually rotatable cam mounted below said arm; said cam including a cam surface adapted to engage said arm and lock said valve in closed position, a cam surface adapted to permit limited opening movement of said valve, a stop adapted to engage said arm, and a cam surface adapted to permit full opening movement of said valve. 35

13. An acetylene generator including in combination, a hopper adapted to contain calcium carbide and having an outlet; a valve controlling said outlet; a pressure-responsive diaphragm

said outlet; a pressure-responsive diaphragm; a lever connecting said valve and said diaphragm; an arm extending from said lever; rotatable means for engaging said arm and locking said valve in closed position, said rotatable means including a member adapted to engage said arm and limit initial rotation of such rotatable means to prevent full opening movement of said valve until the pressure within said generator has 10 reached a predetermined value.

10. An acetylene generator as claimed in claim 2, including means for engaging said lever to lock said valve in closed position.

11. An acetylene generator as claimed in claim 15 2, including means for engaging said lever to lock said valve in closed position, said means being adapted to move said lever toward said diaphragm and to compress said spring.

12. An acetylene generator as claimed in claim 20 2, including means for engaging said lever to lock said valve in closed position, said means being adapted to move said lever toward said diaphragm and to compress said spring, and said spring being adapted to move said lever away 25 from said diaphragm when said locking means is released to insure positive opening of said valve.

13. An acetylene generator including in combination, a hopper adapted to contain calcium 30 carbide and having an outlet; a valve for controlling said outlet; a pressure-responsive dia-

phragm; a lever mounted on said generator and pivotally secured to said valve and to said diaphragm; an arm integral with said lever and extending therefrom; a rotatable cam disposed in operative relation to said arm; said rotatable cam including a first cam surface adapted to engage said arm and lock said valve in closed position, a second cam surface adapted to permit said valve to open a limited amount, a third cam surface adapted to permit said valve to open 10 to its full extent, and a lug extending outwardly from said cam between said second and third cam surfaces and adapted to engage said arm to prohibit further rotation of such cam until the pressure within said generator has reached 15 a predetermined value.

14. An acetylene generator including in combination, a hopper having an outlet; a valve controlling said outlet; a pressure-responsive diaphragm so positioned as to be affected by the 20 gas pressure in said generator; means for locking said valve; means operatively connecting said diaphragm and said valve, said means including a lost motion connection whereby said diaphragm may move when said valve is locked; and a resilient member normally opposing said 25 lost motion connection and being of sufficient rigidity to move said valve when said locking means is disengaged.
